UNITED STATES PATENT OFFICE.

CATHRINE L. HORTON, OF MILWAUKEE, WISCONSIN.

SKIRT-HANGER.

SPECIFICATION forming part of Letters Patent No. 779,081, dated January 3, 1905.

Application filed February 9, 1904. Serial No. 192,733.

To all whom it may concern:

Be it known that I, CATHRINE L. HORTON, residing at Milwaukee, in the county of Milwaukee and State of Wisconsin, have invented 5 a new and useful Improvement in Skirt-Hangers, of which the following is a description, reference being had to the accompanying drawings, which are a part of this specification.

10 This invention relates to certain new and useful improvements in skirt-hangers, and has for its object to provide a support which will fill out the upper portion of a skirt in its natural shape, and so cause the entire skirt to 15 hang therefrom in a perfectly natural state.

A further object is to render such a support adjustable to vary the waist and hip measurements and by them to change the general contour of the support to suit requirements.

20 Another object of this invention is to enable the hanger to be readily collapsed, so as to occupy a small space for packing or storing.

With the above and other objects in view 25 the invention consists in the devices and parts and their equivalents, as hereinafter set forth.

Referring to the accompanying drawings, in which like characters of reference indicate the same parts in the several views, Figure 1 30 is a sectional elevation of a skirt-hanger embodying my invention. Fig. 2 is a plan view thereof, and Fig. 3 is a detail plan view of the runner.

In the drawings, 5 represents a guide rod or 35 stem, which may be of any suitable shape and material, but which is preferably a round wooden bar, as shown. Near the upper end of the rod 5 is adjustably clamped a crown-sleeve 6, having a thumb-screw 7 threaded in a boss 40 thereof and engaging a friction-shoe 8, which consists of a strip of sheet metal loosely held within a longitudinal groove in the bore of said crown-sleeve by having its ends bent outwardly against the ends thereof. The turning 45 of the thumb-screw 7 against the friction-shoe 8 presses said shoe against the rod 5 to securely clamp said rod, and so prevent accidental movement of the crown-sleeve on the rod. At the lower end the crown-sleeve 6 is 50 provided with an outwardly-extending annu-

lar flange 9, which is provided with a series of radial slots 10, each being provided with a pivot-pin 11, extending thereacross.

Slidable and adjustable upon the rod 5 below the crown-sleeve 6 is a runner 12 similar 55 to the crown-sleeve, being provided with the thumb-screw 13, threaded in a boss 14 and bearing against the friction-shoe 15 and also having the outwardly-extending annular flange 16 at its upper end provided with radial slots 60 17, which have the pivotal pins 18 thereacross, all parts being similar in all respects to the corresponding parts of the crown-sleeve. The crown-sleeve and the runner, as shown in the drawings, differ only in that the former is 65 shorter than the latter and is inverted, though they may be made precisely alike and may have the same relative positions without affecting their operation.

A series of curved ribs 19, preferably formed 70 of spring-wire, are pivotally mounted in the slots 10 of the crown-sleeve by having their inner ends bent around the pivot-pins 11 therein, and when so mounted they assume radial positions about the rod 5 and are braced 75 against lateral movement by their engagement with the walls of the slots 10. At intermediate points the rib-wires 19 are bent to form inwardly-extending coil-eyes 20, through which are pivoted the looped outer ends of 80 stay-wires 21. Said stay-wires have their inner ends pivotally connected with the pivot-pins 18 of the runner by being bent there-around and are braced against lateral movement by the walls of the slots 17 in the same 85 manner as the pivotal connections of the ribs 19.

It will be seen that the construction so far as described is similar in some respects to the construction of an ordinary umbrella, the radial ribs being braced by stay-wires, having pivotal connections therewith and with the adjustable runner slidable on the guide-rod. However, the runner in the present case is 90 capable of moving higher up on the guide-rod than the plane of the pivotal connections between the stay-wires and the ribs, so that the collapsing operation is the reverse of that of the umbrella, and the runner is located at 95 its highest point on the guide-rod when the 100

device is collapsed instead of at the lowest point, as with the umbrella. As the runner 12 moves upwardly from the position shown in Fig. 1 it first causes the ribs 19 to swing outwardly until the stay-wires 21 reach a horizontal position. Then the further upward movement of the runner permits said stay-wires and ribs to move inwardly, and when the runner has reached its highest position 10 close to the crown-sleeve the stay-wires 21, having their pivots close to the pivots of the ribs, give practically no support to the ribs, and consequently both fold close to the rod 5.

The rib-wires 19 are bent and twisted to 15 form upwardly-extending elongated loops 22 at points intermediate of their inner ends, and the coil-eyes 20 and the portion of said rib-wires between the loops 22 and their inner ends is practically straight and horizontal 20 when said ribs are extended, as shown in Fig. 1, though the remainder thereof is gently curved, as shown in the drawings. The rib-wires are not of the same length, but on one 25 side of the guide-rod 5 they are shorter than on the other side and have shorter stay-wires 21, and the rib-wires with their stay-wires between the extremes are graduated in proportions, as clearly shown in Fig. 2.

At the lower ends of the ribs 19 they are 30 bent back to form vertical elongated loops 23 somewhat similar to loops 22, and through the series of loops 23 is passed an adjustable hip-band 24, preferably of spring sheet metal, having a series of perforations 25 on one end 35 and a projecting stud 26 on the other end to engage with said perforations. Sleeves 27 slide upon the overlapping ends of the hip-band to bind them in their adjusted position by retaining the stud 26 in whichever perforation 25 it has been placed. A waistband 28, similar in all respects to the hip-band 24, is passed through the loops 22 and has its 40 ends adjustable in the same manner as just described for the hip-band.

45 When the device is desired to be set for use with a particular skirt, the waistband 28 is adjusted to assume the size of the internal measurements of the waistband of the skirt and the hip-band 24 is adjusted to assume the 50 size of the hip-measurements of the skirt, the runner 12 being free to slide during such adjustments and the crown-sleeve 6 being rigidly secured to the rod 5. When the two bands have been adjusted as described, the 55 runner 12 may be forced upwardly to bow the ribs 19 to any extent desired and then fastened by turning its thumb-screw 13, or said runner may be fastened to the rod at its natural position produced by the adjustment of 60 the waist and hip bands. Such adjustment of the runner 12 to increase the bow of the ribs 19 may be desirably accomplished after the skirt has been placed upon the hanger and fastened thereon as if on the wearer, and then 65 such bowing of the ribs may be made to ex-

actly fill out the skirt, so that it will hang in its natural position.

Any suitable means may be employed for suspending or supporting the hanger, and I have shown for that purpose a vertical wire 70 loop 29, having a horizontal stem with an eye on its end which is engaged by a screw 30, turned in the end of the rod 5. The loop 29 extends toward the front of the hanger, where it may be engaged with a clothes-hook or the 75 like in a closet or wherever it is desired to hang the skirt.

If it is desired to store or pack the skirt-hanger, the waist and hip bands are removed from their respective loops and the runner 12 80 is raised to its highest position, when the ribs 19 swing inwardly, as before described, and may be fastened in their collapsed condition by any suitable means, such as by having the 85 waist or hip bands wound thereabout.

While I have shown and described features in detail as I prefer to use them, I do not wish to be limited thereto, for it is obvious that many changes may be resorted to in accomplishing the same or practically the same results by altering such details and without departing from the spirit and scope of my invention. For instance, the crown-sleeve 6 90 may be rigidly attached to the rod 5, or the ribs and stay-wires may be pivoted together 95 and to the crown-sleeve and runner in any other desirable manner, or the waist and hip bands may be made of other material, though, as above stated, these details are preferred at 100 present.

The crown-sleeve 6 is preferred to be adjustable upon the rod 5 in order that the 105 waistband may be adjusted after the hip-band has been adjusted and to render the bowing operation of the rib-wires more easily 110 accomplished while the skirt is being held thereby, inasmuch as said crown-sleeve is more accessible at such time than the runner 12.

115 It is also obvious that the principles of my invention are not restricted to skirt-hangers, but may be employed with other devices, such as coat-hangers and the like, and therefore I do not limit myself to their application to any particular use, but reserve the right to apply them to whatever uses they may be susceptible of.

120 What I claim as my invention is—

1. In a skirt-hanger, a guide-rod, ribs pivotally mounted thereon, means for supporting the ribs in an extended position, and a band connecting the ribs comprising a strip of sheet metal provided with means for adjustably connecting its ends.

125 2. In a skirt-hanger, a guide-rod, ribs pivotally mounted thereon, means for supporting the ribs in an extended position, and a band connecting the ribs comprising a strip of sheet metal, one end of the strip being provided with a series of perforations, a stud 130

on the other end of the strip to engage in the perforations, and sleeves surrounding the ends of the strip to hold the stud in the perforations.

5. 3. In a skirt-hanger, a guide-rod, wire ribs pivotally mounted thereon, means for supporting the ribs in an extended position, loops bent and twisted in the ribs, and a band passing through said loops.

10. 4. In a skirt-hanger, a guide-rod, a sleeve adjustable thereon, wire ribs pivoted to the sleeve, coil-eyes bent in the ribs, wire stays having looped ends engaging the coil-eyes of the ribs, a runner adjustable on the guide-rod

15. to which the stays are pivoted, loops bent and twisted in the ribs, an adjustable waistband passing therethrough, loops bent at the ends of the ribs, an adjustable hip-band passing therethrough, and means on the guide-rod by

20. which the hanger may be supported.

5. In a skirt-hanger, a guide-rod, resilient ribs pivotally mounted thereon, a hip-band and a waistband connecting the ribs, a sleeve adjustable on the guide-rod, and stays pivoted 25 to the sleeve and connecting with the ribs between the two bands whereby the movement of the sleeve on the guide-rod causes the ribs to bow more or less between the bands.

6. In a skirt-hanger, a guide-rod, resilient 30 ribs pivotally mounted thereon, waist and hip bands connected to the ribs, a sleeve slideable on the guide-rod, stays pivoted to the sleeve, and loops formed in the ribs between the bands, said stays having looped ends engaging 35 the loops of the ribs whereby the ribs are caused to be bowed between the bands by the adjustment of the sleeve on the guide-rod.

7. In a skirt-hanger, a guide-rod, ribs having 40 pivotal connection therewith, said ribs being bent to form loops, a band passing through the loops of the several ribs, and means for distending the ribs.

8. In a skirt-hanger, a guide-rod, ribs having 45 pivotal connection therewith, said ribs being bent to form loops, a band passing through the loops of the several ribs, a sleeve slideable on the guide-rod, and stays connecting the sleeve with the ribs.

9. In a skirt-hanger, a guide-rod, ribs having 50 a pivotal connection therewith, said ribs

provided with a straight horizontal portion at their pivoted ends and being bent at the ends of the horizontal portions to produce upwardly-extending loops with the remaining portion extending downwardly, a waistband 55 passing through the upwardly-extending loops of the ribs, and means for supporting the ribs.

10. In a skirt-hanger, a guide-rod, ribs having a pivotal connection therewith, said ribs having a horizontal portion at their pivoted 60 ends and being bent to form upwardly-extending loops at the ends of the horizontal portions with their remaining portions extending downwardly and bent to form intermediate loops and end loops, bands passing through 65 the upwardly-extending loops and the end loops of the ribs, a sleeve adjustable on the guide-rod, and stays pivotally connected to the sleeve and to the intermediate loops of the ribs.

11. In a skirt-hanger, a guide-rod, ribs having pivotal connection therewith, means for supporting the ribs, a circular waistband connected to the ribs and a circular hip-band connected to the ribs, said ribs varying in their 75 relative proportions so that the guide-rod will be eccentric to the circular bands.

12. In a skirt-hanger, a guide-rod, ribs having a pivotal connection therewith, means for distending the ribs, a circular waistband connecting the ribs, and a circular hip-band connecting the ribs, said ribs differing in their 80 relative proportions whereby the circular waistband and the circular hip-band will be eccentric to each other and the guide-rod will 85 be eccentric to both.

13. In a skirt-hanger, a guide-rod, ribs having a pivotal connection therewith, means for distending the ribs, a circular waistband having connection with the ribs, and a circular 90 hip-band having connection with the ribs, said ribs differing in their relative proportions whereby the circular waistband is eccentric to the circular hip-band.

In testimony whereof I affix my signature in 95 presence of two witnesses.
